UNITED STATES PATENT OFFICE.

MAHLON E. LAYNE, OF HOUSTON, TEXAS.

WELL-BORING STEM.

1,223,591.

Specification of Letters Patent. Patented Apr. 24, 1917.

Application filed December 1, 1913. Serial No. 803,889.

To all whom it may concern:

Be it known that I, MAHLON E. LAYNE, a citizen of the United States, residing at Houston, in the county of Harris and State 5 of Texas, have invented certain new and useful Improvements in Well-Boring Stems, of which the following is a specification.

The invention relates to well boring stems, and particularly to the coupling means for 10 the sections of tubing comprising the stem. The invention has for its primary objects; the provision of a construction wherein the tendency of the stem to buckle at the couplings is eliminated; the provision of a coupling structure wherein the outside diameter 15 of the stem at the coupling is maintained the same as at other portions of the stem while still providing means for securing a positive grip upon the outside of the stem; the provision of interior securing means which 20 do not materially interfere with the flow of water through the stem and wherein the tendency of the pipe to rupture at the juncture between the pipe and the thickened 25 reinforcing means is reduced; the provision of guide means whereby the tendency of the threads on the coupling members to become injured through misingating is eliminated; and the provision of means whereby the 30 threaded parts can be brought into secure and positive interlocking engagement after the threads have become worn and loosened. Certain embodiments of the invention are 35 illustrated in the accompanying drawings, wherein—

Figure 1 is a longitudinal section through a well boring stem at the coupling or joint, Fig. 2 is a side elevation of the coupling, Fig. 3 is a longitudinal section through 40 the end of the internally threaded coupling member, Fig. 4 is an end view of the internally threaded coupling member, Fig. 5 is a side elevation of the end of the externally threaded coupling member, Fig. 6 is an end 45 view of the last mentioned coupling member, and Figs. 7, 8, and 9 are longitudinal sections through boring stems having modified forms of coupling connections.

Referring first to the construction shown 50 in Figs. 1 to 6, 1 and 2 are the usual tubes which make up the main portion of the boring stem, and 3 and 4 are metal coupling members secured rigidly to the ends of the tubes 1 and 2. In order to secure this rigid 55 connection between the outer ends of the

coupling members 3 and 4 and the tubes, the ends of the coupling members are formed so as to fit inside the tubes and are provided with a series of holes 5 preferably arranged in the form of spirals as indicated in Fig. 2. 60 The ends of the tubes preferably abutting the shoulders 6 and 7, and after the tubes have been fitted in place over the ends of the coupling members the metal of the tubes is punched into the recesses 5 as indicated 65 in Fig. 1. This forcing in of the metal of the tubes may be accomplished in any desired way, but is preferably done by passing the couplings under rotating drums provided with properly spaced punches. 70

As indicated in Figs. 3 and 5, the member 4 is provided with an internally tapering portion having the screw threads 8, while the member 3 is provided with an external tapering portion provided with the screw 75 threads 9 adapted to coöperate with the screw threads 8. In order to guide the two parts into position and avoid injury to the threads due to misingating, the inner end of the member 3 is provided with a cylindrical 80 portion 10 adapted to fit into the portion 11 on the member 4. After the two members have been telescoped into position they can be rigidly screw threaded together by a relatively slight amount of rotation. 85

In order to provide for a certain amount of adjustment between the screw threaded members, the annular washers 12 (Fig. 1) are provided between the end of the member 4 and the shoulder 13 on the member 3. 90 If the thread should wear and become loose a washer can be removed, which permits of a slight further relative rotation of the coupling members to bring the screw threads into tight locking engagement. In order to 95 provide for slight cutting action when the members are rotated to a new position to take up wear, the threaded portions of the two members are provided with the longitudinal grooves 14 and 15, which grooves 100 cause the threaded portions to act somewhat as dies. The groove also serves to carry lubricant.

By reference to Fig. 1 it will be noted that the ends of the members 3 and 4 are 105 tapered at the portions marked 16. These tapered portions act somewhat as nozzles, so that there is very little retardation of the liquid due to the contracted portions, and further serve to reduce the tendency of the 110

tubes to fracture at the juncture between the coupling members and the tubes. That is, there is a slight amount of resiliency at the ends of the coupling members, and the strain upon the tube due to lateral bending action is not as severe as would be the case if the reinforcing means upon the interior were absolutely rigid. It will be further noted that the exterior diameter of the coupling members intermediate the ends of the tubes 1 and 2 is substantially that of the tubes themselves, so that there is no added resistance to the downward movement of the stem due to the coupling, since the coupling members pass as readily through the various strata as do the tubes themselves.

In order to provide means for securely gripping the stem the material of the member 3 is cut away, forming the groove 17, which can be engaged by any desired lifting means.

A modified structure is illustrated in Fig. 7 wherein the coupling means 18 and 19 are formed by upsetting the ends of the tubes 20 and 21. The screw threaded connection is the same as heretofore described in connection with Fig. 1, and the washers 22 permit of the adjustment heretofore described. In this structure two gripping recesses 23 are provided, one on each of the coupling members. This is the strongest of the various structures and preferred for that reason.

In the construction of Fig. 8 the coupling members 24 and 25 are provided at their outer ends with corrugations 26, into which corrugations the metal of the tubes 27 and 28 is rolled, the members being supported during such operation by means of mandrels. The construction in other respects is substantially the same as heretofore described in connection with Fig. 1.

In the construction of Fig. 9 the tubes 29 and 30 are shrunk upon the ends of the coupling members 31 and 32, and in order to give additional security the triangular rings 33 fitting in recesses between the coupling members and tubes are welded to such parts, thus giving a very secure connection at the ends of the tubes. In this construction no washers like the washers 12 of Fig. 1 are used, the end of the member 31 coming in contact with the shoulder 34 on the member 32. As the threads between the two members wear and it becomes necessary, the end of the member 31 can be turned or ground off, thus permitting the members to be screwed closer together. This modification is of course applicable to all the various forms of construction.

What I claim is—

1. In combination in a well boring stem, a pair of tubes, reinforcing tubular coupling means at the ends of the tubes having a tapering screw connection, the interior

diameter of the reinforcing coupling means at their meeting ends being less than the interior diameter of the tubes, with a gradually increasing diameter from the portions of reduced diameter to the other ends of 70 the reinforcing means.

2. In combination in a well boring stem, a pair of tubes, reinforcing coupling means at the ends of the tubes having a tapering screw connection, the said coupling means being tapered internally at their outer ends and having their interior diameter at their inner ends materially reduced from that of the interior diameter of the tubes.

3. In combination in a well boring stem, 80 a pair of tubes, reinforcing coupling means at the ends of the tubes having a tapering screw connection, the said coupling means being tapered internally at their outer ends and having their interior diameter at their inner ends materially reduced from that of the interior diameter of the tubes, and the exterior diameter of the coupling means being substantially the same as that of the said tubes.

4. In combination in a well boring stem, a pair of tubes, a reinforcing coupling means at the end of one tube having a tapering externally threaded portion and a cylindrical guide portion in advance of 95 the threaded portion, and a second reinforcing coupling means at the end of the other tube having a tapering internally threaded portion and a portion to the rear thereof formed to receive and fit the said 100 guide portion on the first coupling means.

5. In combination in a well boring stem, a pair of tubes, a reinforcing coupling means at the end of one tube, having a tapering externally threaded portion and an external stop portion, a second reinforcing coupling means at the end of the other tube having an internally tapering threaded portion and a stop portion opposing the stop portion on the other coupling means, 110 and a plurality of washers between the said stop means, clearance being provided in the second coupling means opposite the end of the first mentioned coupling means whereby the coupling means may be screwed farther 111 together on the removal of one of the washers.

6. In combination in a well boring stem, a pair of tubes, a reinforcing coupling means at the end of one tube having a tapering externally threaded portion, a second reinforcing coupling means at the end of the other tube having an internally tapering threaded portion, opposing stop means on the two coupling means, and a 12 washer between the stop means, one of the said threaded portions being longitudinally grooved.

7. In combination in a well boring stem, 120 a pair of tubes, a reinforcing coupling

means at the end of one tube having a tapered externally threaded portion, and a second reinforcing coupling means at the end of the other tube having an internally 5 tapering threaded portion, said threaded portions being longitudinally grooved.

In testimony whereof I have hereunto

signed my name in the presence of the two subscribed witnesses.

MAHLON E. LAYNE.
